Milwaukee, Wis.

Filed Oct. 6, 1959, Ser. No. 844,772
6 Claims. (Cl. 336—217)

This invention relates to electric induction apparatus and more particularly to a laminated core structure for a three phase transformer.

At one time, the layers of three phase stacked laminated transformer cores comprised three leg pieces and four yoke pieces, all of which were rectangular. Thus, all of the leg pieces were identical and likewise the yoke pieces were identical. As development continued, it was discovered that certain grades of magnetic sheet material which had been hot rolled have a higher degree of permeability in the direction of rolling as compared to other directions. It was also learned that losses are least when the flux lines are parallel to the direction of rolling instead of across the grain. In order to take full advantage of steel having a preferred magnetic direction, leg and yoke pieces have been made with diagonal or mitered ends. The resulting mitered butt joints permit the lines of flux to form in the direction of least magnetization throughout the core layers. It was further learned that by staggering or overlapping the mitered butt joints of adjacent layers to avoid coincident joints, separation of the laminations is minimized.

As the above developments occurred, it was only natural that the individual pieces comprising a core became more complex in their configuration. The number of different configurated pieces in each layer also increased with as many as four different pieces comprising one layer of a three phase core. Thus, while transformers became more and more efficient, the cost of making the various pieces for the core also increased.

The three phase core of this invention uses pieces of only two different configurations which are relatively simple in design and yet still form an advantageous butt lapped mitered joint structure. The three leg pieces in each layer of the core are identical in configuration, as are the four yoke pieces. With the need for only two different configurated pieces in a layer, stock piling becomes relatively simple since only two piles are required. Set up time is also reduced. By providing the end portions of the leg pieces with tapered ends, the outside right angle corners normally present in an assembled core are eliminated and consequently a lighter core is provided.

Thus, it is one object of this invention to provide a new and improved three phase laminated core having butt lapped mitered joints.

Another object of this invention is to provide a new and improved three phase core having reduced weight.

Another object of this invention is to provide a new and improved three phase core in which each layer comprises pieces having only two different shapes.

Another object of this invention is to provide a new and improved laminated core having efficient magnetic characteristics which may be manufactured at a reduced cost.

Further objects and advantages of the present invention will be apparent from the description and accompanying drawings, and will be more particularly pointed out in the claims.

In the accompanying drawing:

FIG. 1 illustrates an arrangement of stacked layers of magnetic sheet material arranged in accordance with this invention;

FIG. 2 illustrates a modification of this invention.

2

The structure shown in FIG. 1 illustrates a three phase core 10 having but lapped mitered core joints in accordance with this invention. Legs 11 and yokes 12 of the core are identical in width and are formed from strip material which has higher permeability in the lengthwise direction which is the direction of rolling. The three leg pieces 11 are identical in configuration. The leg and yoke pieces have all been cut with their lengths parallel to the most favorable magnetic direction in order to obtain a highly efficient transformer. Each leg has two extending end portions 14 with each of the end portions being outlined by two edges 16 and 17 which converge to form acute angles A. The angle edges 16 and 17 are preferably positioned in such a manner that a line bisecting the angle A therebetween is parallel to the longitudinal center line 18 of the leg. In the preferred embodiment, apex 19 of each angle A forming the end portions is on a line offset or askew with longitudinal center line 18. The end 19 of each of the end portions also terminates within the area bordered by an extension of the lines forming the longitudinal edges of the leg piece. Each yoke piece 12 is in the shape of an isosceles trapezoid which adds to the simplicity of assembly. If the bisecting line of the angle A is not parallel to the longitudinal center line, then the yoke is a trapezoid in which the non-parallel edges are unequal in length.

Overlapping of core joint 21 is achieved by providing each leg piece with a pointed end. The point 19 of each end is preferably offset from the center line 18. In this manner, each layer in the core can have its joint edges offset from the joint edges in adjacent layers, affording an overlapping effect on the joints. In assembling the core, the leg pieces in one layer are arranged inversely congruent to the superposed leg pieces in adjacent layers. Since the leg pieces are unsymmetrical with respect to their longitudinal center line 18, it is relatively easy to arrange the layers to obtain butt lapped joints. The leg pieces 11 in alternate layers are identically positioned while the leg pieces in the adjacent layers may either have their ends 19 reversed or be turned over to stagger the edges 16 and 17. In such a manner, the assembly of three phase cores is relatively easy. There need be only two stock piles of core pieces and consequently there is considerable ease in assembling the two pieces to form a three phase core. The fact that the core of this invention does not have rectangular corners which have heretofore appeared in three phase transformers of the prior art is not a limiting one. The lack of rectangular corners does not cause any excessive losses as the core cross section taken perpendicular to the flux remain substantially as large in the corners as in the remainder of the core. The weight of the core is thereby reduced without affecting the performance characteristics of the transformer.

The preferred embodiment illustrated in FIG. 1 has leg pieces having an end portion 14 with an angle A of 53°-10'. Angle B between a joint edge 21 and edge 22 of yoke 12 is 63°-25'. While the angle A of the end portion of the leg pieces could be less, it is believed that the angle of approximately 53° will provide the best pattern for providing the least flux resistance. When the end angle A is less than 53°, one of the mitered junction lines defining end portion 14 will approach a perpendicular position with respect to the adjoining yoke 12 and consequently the resulting structure is less efficient.

FIG. 2 illustrates a second embodiment of the invention. Leg pieces 26 have two edges 27 and 28 which are equal in length. The result is that the overlap between junction line 31 in one layer and junction line 32 in an adjacent layer is tapered with the overlap being widest at the outer perimeter of the core. The advantage in this, which has previously been recognized, is that the joint reluctance at the outer perimeter is reduced

thereby offsetting the greater reluctance which normally occurs at the longer perimeter. In such a manner, the total reluctance is more uniform and the flux lines are more equally distributed. Heretofore, three phase cores having this feature required four different dies to stamp out the pieces comprising each layer. The structure in the embodiment of FIG. 2 retains the advantages of the prior art while requiring only two dies.

Although but two embodiments have been shown and described, it will be apparent to those skilled in the art that various changes and modifications may be made therein without departing from the spirit of the invention or the scope of the appended claims.

Having now particularly described and ascertained the nature of our said invention and the manner in which it is to be performed, we declare that what we claim is:

1. A magnetic core for three phase electrical apparatus comprising: a plurality of layers of magnetic sheet material, each said layer having three leg pieces of like configuration and four yoke pieces of like configuration connecting said leg pieces to form two substantially rectangular windows, said leg and yoke pieces having the same width, each said leg having two extending end portions, each said end portion formed by two edges converging in directions acute with the longitudinal center line of said leg, the apex of the angle formed by the edges of one of said end portions being offset from said center line, each said yoke piece defining a trapezoid, and each said layer having its pieces inversely congruent to said superposed pieces in said adjacent layers whereby the superposed joint edges in said adjacent layers provide an overlap.

2. A magnetic core for three phase electrical apparatus comprising: a plurality of similar layers of magnetic sheet material, each said layer having three leg pieces of like configuration and four yoke pieces of like configuration connecting said leg pieces to form a substantially rectangular core, said leg and yoke pieces being of the same width and having their lengths parallel to the most favorable magnetic direction of said material, each said leg piece having each end defined by joint edges terminating at a point within the area bordered by an extension of the lines forming the longitudinal edges of said leg piece with at least one of said end points being offset from the longitudinal center line of said leg piece, each said yoke piece forming an isosceles trapezoid, and each said layer having its pieces inversely congruent to said pieces in adjacent layers whereby said joint edges in a layer are overlapped by said pieces in said adjacent layers.

3. A magnetic core for three phase electrical apparatus comprising: a plurality of similar layers of magnetic sheet material, each said layer having three leg pieces of like configuration and four yoke pieces of like configuration connecting said leg pieces to form two substantially rectangular windows, said leg and yoke pieces being of the same width and having their lengths parallel to the most favorable magnetic direction of said material, each said leg piece having each end defined by joint edges terminating at a point within the area bordered by an extension of the lines forming the longitudinal edges of said leg piece with at least one of said end points before offset from the longitudinal center line of said leg piece, each

said yoke piece forming a trapezoid, and each said layer having its leg pieces inversely congruent to said leg pieces in adjacent layers whereby said joint edges in a layer are overlapped by said pieces in adjacent layers.

4. A magnetic core for three phase electrical apparatus comprising: a plurality of layers of magnetic sheet material, each said layer having three leg pieces of like configuration and four yoke pieces of like configuration connecting said leg pieces to form two substantially rectangular windows, said leg and yoke pieces have the same width with their lengths parallel to the most favorable magnetic direction of said material, each said leg having two extending end portions, each said end portion formed by two edges defining an acute angle whereby a line bisecting said angle is parallel and offset from the longitudinal center line of said leg, each said yoke piece defining an isosceles trapezoid, and each said layer having its pieces inversely congruent to said superposed pieces in said adjacent layers whereby said joint edges in a layer are overlapped by said pieces in said adjacent layers.

5. A magnetic core for three phase electrical apparatus comprising: a plurality of similar layers of magnetic sheet material, each said layer having three leg pieces of like configuration and four yoke pieces of like configuration connecting said leg pieces to form two substantially rectangular windows, said leg and yoke pieces being of the same width and having their lengths parallel to the most favorable magnetic direction of said material, each said leg piece having each end defined by joint edges terminating at a point within the area bordered by an extension of the lines forming the longitudinal edges of said leg piece with at least one of said end points being offset from the longitudinal center line of said leg piece, each said yoke piece forming a trapezoid, and each said layer having its leg pieces inversely congruent to said leg pieces in adjacent layers whereby said joint edges in a layer are overlapped by said pieces in adjacent layers and parallel to the respective joint edges in adjacent layers.

6. A magnetic core for three phase electrical apparatus comprising: a plurality of similar layers of magnetic sheet material, each said layer having three leg pieces of like configuration and four yoke pieces of like configuration connecting said leg pieces to form two substantially rectangular windows, said leg and yoke pieces having their lengths parallel to the most favorable magnetic direction of said material, each said leg piece having each end defined by joint edges terminating at a point within the area bordered by an extension of the lines forming the longitudinal edges of said leg piece with at least one of said end points being offset from the longitudinal center line of said leg piece, each said yoke piece forming an isosceles trapezoid, and each said layer having its leg pieces inversely congruent to said leg pieces in adjacent layers whereby said joint edges in a layer are overlapped by said pieces in adjacent layers and parallel to the respective joint edges in adjacent layers.
